SLIDE FASTENER

Albert Bashover, Newark, N. J., assignor to Conmar Products Corporation, Newark, N. J., a corporation of New Jersey

Application February 14, 1951, Serial No. 210,900

18 Claims. (Cl. 24—205.14)

1

This invention relates to slide fasteners, especially automatically locking sliders, and more particularly to such a slider which may be operated from either side of the fastener.

There are a number of applications of slide fasteners in which it is desirable to be able to operate the slider from either side of the fastener. The slider of such a fastener is commonly called a "reversible" slider. The primary object of the present invention is to provide a reversible slider which is of the automatically locking type. This requires not only a finger piece on each side of the slider, as is usual with reversible sliders, but also appropriate connections so that either finger piece will unlock the automatic lock.

To develop and perfect an automatic lock slider is a costly task. One object of the present invention is to provide reversible slider mechanism which is applicable to standard sliders, that is sliders which have been perfected and commercialized already.

Still another object of the present invention is to provide reversible slider mechanism which is not peculiarly dependent on the construction of the finger piece or "pull," and which accordingly may be employed with any of a number of forms of finger piece, such as a stiff pivoted pull, a chain pull, or a sliding button-type finger piece.

To accomplish the foregoing general objects, and other more specific objects which will hereinafter appear, my invention resides in the reversible automatic lock slider elements, and their relation one to another, as are hereinafter more particularly described in the following specification. The specification is accompanied by drawings in which:

Fig. 1 is a plan view of a reversible automatic lock slider embodying features of my invention;

Fig. 2 is a section taken approximately in the plane of the line 2—2 of Fig. 1;

Fig. 3 is a section similar to Fig. 2 but showing the slider in unlocked condition;

Fig. 4 is a perspective view of an adapter which is added to an otherwise standard automatic lock slider, to convert the same into the reversible lock slider shown in Figs. 1, 2 and 3;

Fig. 5 is a plan view of a modified form of the invention;

Fig. 6 is a section taken in the plane of the line 6—6 of Fig. 5;

Fig. 7 is a perspective view of a modified adapter employed in the slider of Figs. 5 and 6;

Fig. 8 is a plan view of still another form of

2

the invention utilizing a button-type finger piece; Fig. 9 is a side elevation of the same;

Fig. 10 is a section taken approximately in the plane of the line 10—10 of Fig. 8;

Fig. 11 is a back view of still another modification of the invention;

Fig. 12 is a section taken approximately in the plane of the line 12—12 of Fig. 11; and

Fig. 13 is a perspective view of an adapter forming a part of the slider shown in Figs. 11 and 12.

Referring to the drawing, all forms of the invention have in common the use of a slider body B having a latch L with a locking tooth T and a cam surface C for moving the latch to release the locking tooth. These parts may be conventional. In all cases there is added to the slider a yoke-like adapter A which is disposed around the slider body B at the neck end, and which is 10 slidable for a limited distance longitudinally of the slider. Some form of back finger piece or pull P is provided on the back of the adapter A, and there is also a front finger piece F. The finger pieces P and F may be connected to and 15 carried by the adapter A as separately formed elements, or they may be carried by the adapter by being formed as a part or parts thereof. Appropriate means M is provided at the front of the adapter for so cooperating with the finger piece F and the cam surface C that a movement 20 of either finger piece in fastener-opening direction, that is to the right as shown in Figs. 2 and 3, will cause release of the locking tooth.

Considering the invention in greater detail, 25 and referring more particularly to Figs. 1 through 4 of the drawing, the specific slider body B and latch L are of a standard form disclosed in U. S. Letters Patent 2,523,740 issued September 26, 1950, to Frederick Ulrich and Claude Disinger, and disclosed in their pending patent application Serial No. 89,876, filed April 27, 1949. The

30 sides of the latch are shaped to form resilient or spring arms S which serve to urge the locking tooth inward to locking position. There are 35 preferably two teeth, slightly staggered to engage the elements E on the two stringers of the fastener.

There are two cam surfaces C formed on opposite sides of the latch. The finger piece F is 40 provided with inwardly directed trunnions or projections J2 which are anchored beneath the cam surfaces C. It will be evident that when the finger piece is moved in fastener-closing direction the locking teeth may simply ratchet 45 over the fastener elements. When the finger

piece is moved in fastener-opening direction, that is to the right as shown in Fig. 2, the trunnions 12 bear against the cam surfaces C and so raise the latch from the position shown in Fig. 2 to that shown in Fig. 3, at which time the teeth are disengaged from the elements E of the fastener, as is clearly shown in Fig. 3.

Now in accordance with the present invention the adapter A is a yoke-like member which is disposed around the slider body B at the neck end of the slider, and which adapter is slidable for a limited distance longitudinally of the slider. The back finger piece or pull P is secured to the back arm 14 of the adapter, as by means of the bent or channel portion 16. The front arm of the adapter is preferably bifurcated, as shown at 18 in Fig. 4, to straddle the latch L, and the bifurcations 18 have inwardly directed projections 20 which are received beneath the cam surfaces C immediately adjacent the pull trunnions 12. It will be understood that the slider may be actuated by the rear finger piece P, for when it is pulled in fastener-closing direction the teeth simply ratchet over the fastener elements, and when it is pulled in fastener-opening direction it causes the adapter A to move slightly relative to the slider body, as is shown by the change from Fig. 2 to Fig. 3 of the drawing, and the projections 20 bear against the projections 12 and cause the same to move exactly as though the upper finger piece F were being actuated. The resulting movement of the trunnions 12 raises the cam surfaces, and consequently the latch and locking teeth.

It may be mentioned that the particular slider nod here shown is a one-piece body having upper and lower wings 22 and 24 integrally connected by a neck 26, the said wings having flanges or rails 27 which, together with the neck, form the usual Y-shaped slider channel. The upper wing 22 is preferably formed with an integral fixed lug. This lug is indicated at 28. It is displaced or excised outwardly, and is indented at the sides to form elongated indentations which are long enough to accommodate the desired unlocking movement of the projections 12 and 20 longitudinally of the slider. As is best shown in Fig. 1 of the drawing, the trunnions 12 of the finger piece F are preferably projected inwardly far enough to enter the side indentations of the fixed lug. This, of course, greatly strengthens the connection of the finger piece to the slider body, for it may be considered to be permanently connected to the fixed lug, and need not rely on the connection to the latch.

The latch L is preferably formed out of sheet metal bent to provide an inverted, trough-like, hollow body dimensioned to be received around the outside of the fixed lug 28. The lug acts to take up the force exerted by the trunnions, which otherwise would be transmitted entirely to the latch. Because of the inwardly projecting trunnions 12 there is a camming action at the outer portions of the trunnions, and an anchoring action at the inner ends of the trunnions.

The inward projections 20 of the adapter may be and preferably are extended inward as far as are the trunnions 12, as shown in Fig. 1, so that the adapter is independently and permanently anchored to the slider by means of the fixed lug 28, apart from the movable latch L. The engagement of the projections 20 with the lug limits the longitudinal movement of the adapter so that the adapter is prevented from sliding off the slider body B.

Referring now to the modified form of the in-

vention shown in Figs. 5, 6 and 7, this employs identically the same slider body B, latch L, and fixed lug 28 as was previously described. The adapter, however, is shaped somewhat differently. As before, it is bent around the slider body, and the forward or upper arm is bifurcated to straddle the latch L, the resulting bifurcations being numbered 30. These are disposed edgewise, and are transversely notched at their lower edges, as is indicated at 32. The upper finger piece or pull F has trunnions 34 of increased length, that is, the spacing between the arms 36 of the pull (Fig. 5) is increased enough to provide room for the arms 30 of the adapter. The notches 32 are dimensioned to receive the trunnions 34, as shown in Fig. 6.

The operation of this form of the invention is substantially the same as previously described, for movement of the finger piece F in opening direction cams the latch outwardly to unlocked position, and movement of the back finger piece P in the same direction is applied to the adapter, which in turn causes a corresponding movement of the trunnions 34, and consequently a camming action to release the latch.

As so far described, the slider has had ordinary pivoted pulls. These pulls have been shown as rigid members, but it will be understood that either or both pulls may be replaced by flexible chain pulls. However, it is not essential that the finger piece be a pull, and a modified form of the invention in which the finger pieces are of the button-type is shown in Figs. 8, 9 and 10 of the drawing. Referring to those figures, the slider body B is the same as previously described, and is provided with a fixed lug 28 and a movable latch L, exactly as previously described. The finger piece F on the front side of the slider is of the button-type described and claimed in a co-pending application of Frederick Ulrich, Serial No. 206,746, filed January 19, 1951. The finger piece consists of a piece of metal of adequate thickness, bifurcated at 40 to provide arms 42 which straddle the latch L. These have inwardly directed projections 44 which come beneath the cams of the latch. They are also preferably made long enough to enter the elongated side indentations of the fixed lug 28, as best shown in Fig. 10, thus anchoring the finger piece to the slider body independently of the latch. The sides of the finger piece extend for a substantial distance below the projections 44, as shown at 45 in Fig. 8, thus preventing pivoting of the finger piece about the projections, and instead causing the button-like finger piece to lie flat against the surface of the slider body. The outer edges of the finger piece are preferably roughened or serrated, as shown at 46.

Now in accordance with the present invention there is a back finger piece P, and in the particular form here shown, the back finger piece is also of the button-type. The front and back finger pieces are preferably and most simply formed of a single piece of metal. This is bent at 48 to form a yoke which extends around the slider at the neck end thereof, and which is slidable for a short distance longitudinally of the slider. It will be evident from inspection of the drawing that if either the front or back button is moved in fastener-opening direction the projections 44 will cam the latch outwardly, thus raising the locking teeth from the fastener elements.

It will be understood that in the present form 75 of the invention, as in those previously described,

for purposes of analysis and definition there is an adapter A which fits around the slider body at the neck, and which carries a finger piece at the back of the slider. The adapter also carries a finger piece at the front of the slider. In the present form of the invention it happens to be most convenient to form the finger pieces integrally with the adapter, but separate button-like finger pieces might equally well be secured to an adapter.

Moreover, it is not essential to employ button-like finger pieces on both sides of the slider, and it will be understood that the ideas shown in Figs. 1 and 8 may be combined, that is, a pendant type finger piece may be used at the front of the slider in combination with a button-type finger piece at the back, and vice versa. In such case the button-type finger piece is preferably, though not necessarily, formed integrally with the adapter.

The arrangement of Figs. 8, 9 and 10 illustrates the fact that the inward projections of the adapter may perform the camming action, instead of the inward projections of the finger piece. In Figs. 8, 9 and 10 there is only one pair of inward projections 44. These may be considered to be inward projections on the adapter, or they may be considered to be the inward projections of the finger piece. In any event the single pair of projections serves both to anchor the parts on the slider, and to actuate the latch. From comparison with the pending Ulrich application previously referred to it may be said that the inward projections are a part of the finger piece, for they correspond to projections there employed where there is no adapter. On the other hand, even in the form of the invention shown in Fig. 1 the bifurcations of the adapter could be made slightly longer, and the inward projections of the adapter could be employed to cam the latch. In that case the front finger piece should be attached to the adapter, instead of to the latch.

If desired, any of the forms of the invention so far described may be additionally refined and strengthened by the provision of a fixed lug on the back wing of the slider, as well as on the front wing of the slider. Such an arrangement is shown applied in Figs. 11, 12 and 13 of the drawing, to the slider of Fig. 1. In this case the slider body B is generally the same as that previously described, with the exception that the back wing of the slider is excised, and indented at the sides, to form a rear lug 50. The slider body is standard in respect to the automatic lock mechanism, and its only departure from the standard slider is the piercing of the back wing to form the lug 50. This extra operation is readily introduced in the manufacturing process before the slider blank has been bent at the neck. It is already known to provide sliders with front and back lugs to carry front and back pulls, for reversible sliders which are not of the automatic locking type.

The adapter A is generally similar to that shown in Fig. 4, except that the back arm 52 of the adapter is bifurcated as shown at 54 in Fig. 13. This bifurcation permits the back of the adapter to straddle the back lug 50, as shown in Fig. 11. The rear finger piece or pull P may be identical with the front pull, it having inwardly directed projections or trunnions 56 which are held not only beneath the hooks or troughs 58 of the adapter, but also within the side indentations of the fixed lug 50. It is evident that this strengthens the attachment of the pull P to the slider body, and that the adapter then serves

more exclusively the function of transmitting longitudinal motion or shifting of the pull to the front side of the slider, where it is applied to the camming surfaces in order to unlock the latch.

5 It will be understood that the use of a fixed lug on the back of the slider, with a corresponding bifurcation of the back of the adapter, is equally readily applicable to each of the other forms of the invention shown.

10 10 It will be understood that while I have shown the invention applied to an automatic locking slider of one form, that has been done partly because the slider is of preferred form, and also to show that various forms of the invention are applicable to a single automatic lock mechanism. The invention is equally applicable to automatic lock sliders of other types as, for example, that shown in the Norton Patent 1,966,457 issued July 17, 1934.

15 20 It is believed that the construction and operation of my invention, and the method of applying the same to standard lock sliders, as well as the advantages thereof, will be apparent from the foregoing detailed description. It will also be apparent that while I have shown and described my invention in several preferred forms, changes may be made in the structures disclosed without departing from the scope of the invention, as sought to be defined in the following claims.

25 I claim:

30 35 1. A reversible automatic lock slider comprising a slider body having a latch with a locking tooth and a cam surface engaged by a front finger piece for moving the latch to release the locking tooth, said locking tooth and cam surface both being located on the same side of said slider body, a yoke-like adapter disposed around the slider at the neck end and slidable for a limited distance longitudinally of the slider, a back finger piece provided on the back of the adapter, and means at the front of the adapter so cooperating with the front finger piece and the cam surface that a movement in fastener-opening direction of either finger piece releases the locking tooth.

35 40 45 2. A reversible automatic lock slider comprising a slider body having a latch with a locking tooth and a cam surface for moving the latch to release the locking tooth, a yoke-like adapter disposed around the slider at the neck end and slidable for a limited distance longitudinally of the slider, the front of the adapter being bifurcated to straddle the latch, a back finger piece provided on the back of the adapter, a front finger piece, and means at the bifurcated front 50 55 of the adapter so cooperating with the front finger piece and the cam surface that a movement in fastener-opening direction of either finger piece releases the locking tooth.

40 45 50 55 60 65 3. A reversible automatic lock slider comprising a slider body having a latch with a locking tooth and cam surfaces for moving the latch to release the locking tooth, a yoke-like adapter disposed around the slider at the neck end and slidable for a limited distance longitudinally of the slider, the front of the adapter being bifurcated to straddle the latch, a back finger piece provided on the back of the adapter, a front finger piece, and inwardly directed projections at the front of the adapter so cooperating with the front finger piece and the cam surfaces that a movement in fastener-opening direction of either finger piece releases the locking tooth.

65 70 75 4. A reversible automatic lock slider comprising a slider body having a latch with a locking tooth and a cam surface for moving the latch to

release the locking tooth, a yoke-like adapter disposed around the slider at the neck end and slideable for a limited distance longitudinally of the slider, a back finger piece provided on the back of the adapter, a front finger piece having inwardly directed projections received beneath the cam surface, and the front of said adapter having a projection received beneath the cam surface immediately adjacent the aforesaid projections of the front finger piece, whereby movement in fastener-opening direction of the rear finger piece causes the adapter to correspondingly move the front finger piece which in turn acts on the cam surface.

5 5. A reversible automatic lock slider comprising a slider body having a latch with a locking tooth and a cam surface for moving the latch to release the locking tooth, a yoke-like adapter disposed around the slider at the neck end and slideable for a limited distance longitudinally of the slider, the front of the adapter being bifurcated to straddle the latch, a back finger piece provided on the back of the adapter, a front finger piece having inwardly directed projections received beneath the cam surface, and the bifurcated front of said adapter having inwardly directed projections received beneath the cam surface immediately adjacent the aforesaid projections of the front finger piece, whereby movement in fastener-opening direction of the rear finger piece 20 causes the adapter to correspondingly move the front finger piece which in turn acts on the cam surface.

6 6. A reversible automatic lock slider comprising a slider body having a latch with a locking tooth and a cam surface for moving the latch to release the locking tooth, a yoke-like adapter disposed around the slider at the neck end and slideable for a limited distance longitudinally of the slider, the front of the adapter being bifurcated to straddle the latch, a back finger piece provided on the back of the adapter, a front finger piece having inwardly directed projections received beneath the cam surface, and the bifurcated front of said adapter having inwardly directed projections received beneath the cam surface immediately adjacent the aforesaid projections of the front finger piece, whereby movement in fastener-opening direction of the rear finger piece causes the adapter to correspondingly move the front finger piece which in turn acts on the cam surface, the front of said slider having a fixed lug with elongated indentations at the sides, said latch surrounding said lug, and said inwardly directed projections passing through the sides of the latch into the lug.

7 7. A reversible automatic lock slider comprising a slider body having a latch with a locking tooth and a cam surface for moving the latch to release the locking tooth, a yoke-like adapter disposed around the slider at the neck end and slideable for a limited distance longitudinally of the slider, a back finger piece provided on the back of the adapter, a front finger piece having a projection received beneath the cam surface, the front of the adapter having a transverse notch which receives and straddles the aforesaid inwardly directed projection of the front finger piece, whereby movement in fastener-opening direction of the rear finger piece causes a corresponding movement of the adapter and front finger piece.

8 8. A reversible automatic lock slider comprising a slider body having a latch with a locking tooth and a cam surface for moving the latch to

10 release the locking tooth, a yoke-like adapter disposed around the slider at the neck end and slideable for a limited distance longitudinally of the slider, the front of the adapter being bifurcated to straddle the latch, a back finger piece provided on the back of the adapter, a front finger piece having inwardly directed projections received beneath the cam surface, the arms of the bifurcated front of the adapter having transverse notches which receive and straddle the aforesaid inwardly directed projections, whereby movement in fastener-opening direction of the rear finger piece causes a corresponding movement of the adapter and front finger piece.

15 9. A reversible automatic lock slider comprising a slider body having a latch with a locking tooth and a cam surface for moving the latch to release the locking tooth, a yoke-like adapter disposed around the slider at the neck end and slideable for a limited distance longitudinally of the slider, the front of the adapter being bifurcated to straddle the latch, a back finger piece secured to the back of the adapter, a front finger piece having inwardly directed projections received beneath the cam surface, the arms of the bifurcated front of the adapter having transverse notches which receive and straddle the aforesaid inwardly directed projections, whereby movement in fastener-opening direction of the rear finger piece causes a corresponding movement of the adapter and front finger piece, the front of said slider having a fixed lug with elongated indentations at the sides, said latch surrounding said lug, and said inwardly directed projections passing through the sides of the latch into the lug.

20 10. A reversible automatic lock slider comprising a slider body having a latch with a locking tooth and a cam surface for moving the latch to release the locking tooth, a yoke-like adapter disposed around the slider at the neck end and slideable for a limited distance longitudinally of the slider, a finger piece carried by the back of the adapter, a finger piece carried by the front of the adapter, the front of the adapter being bifurcated to straddle the latch and having inwardly directed projections beneath the aforesaid cam surface, whereby movement in fastener-opening direction of either front or rear finger piece releases the locking tooth, at least one of said finger pieces being a button-like element formed integrally with the adapter.

25 11. A reversible automatic lock slider comprising a slider body having a latch with a locking tooth and a cam surface for moving the latch to release the locking tooth, a yoke-like adapter disposed around the slider at the neck end and slideable for a limited distance longitudinally of the slider, a button-like back finger piece carried by the back of the adapter, a button-like front finger piece carried by the front of the adapter, the front of the adapter having an inwardly directed projection beneath the aforesaid cam surface, whereby movement in fastener-opening direction of either front or rear finger piece releases the locking tooth.

30 12. A reversible automatic lock slider comprising a slider body having a latch with a locking tooth and a cam surface for moving the latch to release the locking tooth, a yoke-like adapter disposed around the slider at the neck end and slideable for a limited distance longitudinally of the slider, a button-like back finger piece having serrated edges and formed integrally with the back of the adapter, a button-like front finger piece having serrated edges formed integrally

with the front of the adapter, the front of the adapter being bifurcated to straddle the latch and having inwardly directed projections beneath the aforesaid cam surface, whereby movement in fastener-opening direction of either front or rear finger piece releases the locking tooth.

13. A reversible automatic lock slider comprising a slider body having a latch with a locking tooth and a cam surface for moving the latch to release the locking tooth, a yoke-like adapter disposed around the slider at the neck end and slideable for a limited distance longitudinally of the slider, a button-like back finger piece having serrated edges and formed integrally with the back of the adapter, a button-like front finger piece having serrated edges formed integrally with the front of the adapter, the front of the adapter being bifurcated to straddle the latch and having inwardly directed projections beneath the aforesaid cam surface, whereby movement in fastener-opening direction of either front or rear finger piece releases the locking tooth, the front of said slider having a fixed lug with elongated indentations at the sides, said latch surrounding said lug, and said inwardly directed projections passing through the sides of the latch into the lug.

14. A reversible automatic lock slider comprising a slider body having a fixed lug on its rear wing, and on its front wing a latch with a locking tooth and a cam surface for moving the latch to release the locking tooth, a yoke-like adapter disposed around the slider at the neck end and slideable for a limited distance longitudinally of the slider, the rear of said yoke being bifurcated to straddle the lug, a back finger piece provided on the back of the adapter, said back finger piece having inwardly directed projections entering the fixed lug, a front finger piece, and means at the front of the adapter so cooperating with the front finger piece and the cam surface that a movement in fastener-opening direction of either finger piece releases the locking tooth.

15. A reversible automatic lock slider comprising a slider body having a fixed lug on its rear wing, and on its front wing a latch having a locking tooth at one end and a cam surface, a yoke-like adapter disposed around the slider at the neck end and slideable for a limited distance longitudinally of the slider, the front of said yoke being bifurcated to straddle the latch, and the rear of the yoke being bifurcated to straddle the rear lug, a back finger piece having inwardly directed projections connected to the back of the adapter and to the back lug, a front finger piece having inwardly directed projections secured beneath the cam surface, and the front of said adapter having inwardly directed projections disposed immediately adjacent the projections of the front pull and coming beneath the cam surface, the arrangement being such that movement of either finger piece in fastener-opening direction releases the locking tooth.

16. A reversible automatic lock slider comprising a slider body having a fixed lug on its front wing and another fixed lug on its rear wing, a

latch enclosing the front lug and having locking teeth at one end and cam surfaces at the sides, a yoke-like adapter disposed around the slider at the neck end and slideable for a limited distance longitudinally of the slider, the front of said yoke being bifurcated to straddle the latch, and the rear of the yoke being bifurcated to straddle the rear lug, a back finger piece having inwardly directed projections connected to the back of the adapter and to the back lug, a front pull having inwardly directed projections secured beneath the cam surfaces and to the front lug, and the front of said adapter having inwardly directed projections disposed immediately adjacent the projections of the front pull and coming beneath the cam surfaces and into the front lug, the arrangement being such that movement of either finger piece in fastener-opening direction releases the locking teeth.

17. In combination with an automatic lock slider of the type having a locking latch on one side of the slider, said locking latch being provided with a cam engageable to move the latch to unlocking position, slider-actuating means having an inturned projection received beneath the cam, an adapter comprising a substantially U-shaped member, said member being disposed on the slider with the base of the U adjacent the neck of the slider and with each arm of the U disposed adjacent the slider wings, the arm of the U adjacent the latch side of the slider having an inturned projection received beneath the cam of the latch, the other arm of the adapter being provided with a second slider-actuating means, said second slider-actuating means serving through said adapter to unlock the latch located on the opposite side of the slider.

18. In combination with an automatic lock slider of the type having a locking latch on one side of the slider, said locking latch being provided with a cam engageable to move the latch to unlocking position, slider-actuating means being inturned projections received beneath the cams, an adapter comprising a substantially U-shaped member, said member being disposed on the slider with the base of the U adjacent the neck of the slider and with each arm of the U disposed adjacent the slider wings, the arm of the U adjacent the latch side of the slider being bifurcated and having inturned projections, said projections being received beneath the cam of the latch, the other arm of the adapter being provided with a second slider-actuating means, said second slider-actuating means serving through said adapter to unlock the latch located on the opposite side of the slider.

ALBERT BASHOVER.
